UNITED STATES PATENT OFFICE.

CYRUS CHAMBERS, JR., OF PHILADELPHIA, PENNSYLVANIA.

KILN FOR DRYING BRICKS, &c.

SPECIFICATION forming part of Letters Patent No. 274,907, dated April 3, 1883.

Application filed December 27, 1882. (No model.)

To all whom it may concern:

Be it known that I, CYRUS CHAMBERS, Jr., a citizen of the United States, residing at the city and county of Philadelphia, and State of Pennsylvania, have invented certain new and useful Improvements in Kilns for Drying Bricks, &c., of which the following is a full, clear, and exact description, reference being had to the accompanying drawings, of which—

10 Figure 1 is a transverse vertical section of a drying flue or kiln provided with my improvement. Fig. 2 is a horizontal sectional view on the line *a b*, Fig. 1. Fig. 3 is a vertical longitudinal section on the line *c d*, Fig. 1. 15 Fig. 4 is a plan view of a section of my improved hot-air-diffusing flue shown in the previous figures. Fig. 5 is a section on the line *e f*, Fig. 4.

This invention is an improvement upon a 20 certain apparatus for the artificial drying of bricks and other articles, invented by Harvey Cockell, of Chicago, Illinois, for which he filed an application for Letters Patent on the 21st day of November, 1882, and of which invention and the Letters Patent that may be issued 25 therefor I am the assignee.

Figs. 1, 2, and 3 of the accompanying drawings show an ordinary brick-drying kiln, consisting of a large flue or tunnel, *A*, built 30 of bricks, with a furnace, *D*, at one end and a smoke-stack (not shown) at the other, and provided with a track, *C*, its entire length, upon which are run the usual trucks, *B*, that carry the raw bricks to be dried, suitably hacked 35 thereon. The ends of the kiln are closed and opened by means of sliding doors, and the train of trucks is entered at one end—usually the stack end—and moved out the opposite end. The defect in drying-kilns thus constructed

40 arises, as stated in said Harvey Cockell's application, from the tendency of the heated air to ascend directly from and near the furnace to the roof and upper part of the kiln, and to pass off into the stack without having done 45 its full duty—that is to say, without having taken up all the moisture from the bricks which it is capable of absorbing—and thus, while the upper tiers of the bricks become rapidly dried, the lower tiers dry slowly and at 50 the loss of time and at excessive cost of fuel. Said Cockell remedies this defect in a large

degree by introducing an auxiliary or diffusing flue having numerous perforations, located at the bottom of the kiln or main flue, and extending from over the furnace the whole length, 55 or nearly so, of the main flue, whereby the heated air is more uniformly diffused within the kiln and among the raw bricks to be dried.

My invention relates merely to an improvement in the construction of the diffusing-flue *F*; 60 and it consists in making the same in two parts or sides, with an open space between them at the top, whereby a single central slot, *S*, is secured along the entire length of the flue; and it further consists in combining with the said two 65 parts a means for adjusting the width of the slot, so as to limit the quantity of hot air which may pass up through the latter within a given time, as circumstances may require. One of the means which I have devised is a transverse 70 bar, *N*, provided with slots *O* and bolts or screws *X*, (see Figs. 4 and 5,) whereby the two sides of the flue may be secured at any desired suitable distance apart. These sides *F F* are preferably made of sheet metal, which by reason 75 of its flexibility, allows of the sufficient adjustment of the opening *S* to different widths at various points in its length; or the two sides may be made up of distinct sections, the several openings between which, one successively 80 leading into the other, may be adjusted independently. By means of this central slot (the flue being located along the middle of the bottom of the kiln, below the middle of the trucks *B*) all the hot air arising from furnace *D* is 85 centrally directed and discharged to ascend and become diffused up between the bricks upon the trucks, as indicated by the arrows. Then, having become charged with moisture absorbed from the bricks, it passes off by way 90 of the stack.

Having thus described my invention, I claim as new and desire to secure by Letters Patent—

1. In combination with a drying-kiln, the diffusing-flue having a continuous central 95 opening therein, substantially as and for the purpose set forth.

2. In a kiln for drying bricks and other articles, the combination, with the main flue, of a slotted diffusing-flue located with reference 100 to the furnace and other parts of the kiln as described, and having devices, substantially

- as shown and set forth, for regulating the width of the slot or opening leading from the said diffusing-flue into the main flue.
3. In combination with the main flue of a drying-kiln, the diffusing-flue composed of two independent parts or sides, whereby, by moving one of said parts to or from the other, the width of the opening between them may be altered, substantially as shown and set forth.
4. In combination with the two parts or sides of the flue F, the slotted bar N and bolts X, as and for the purpose specified.
5. The combination of the main flue, the furnace, the tracks adapted to receive the wheels of trucks, and the diffusing-flue extending over the furnaces and provided with a single central slot substantially its entire length, all constructed and operating substantially as and for the purpose described.
- In testimony whereof I have hereunto affixed my signature this 28th day of November, A.D. 1882.
- CYRUS CHAMBERS, JR.
